METHOD OF FLANGING SHEET METAL
CAN BODIES

John Coyle, Baltimore, Md., assignor to Continental Can Company, Inc., New York, N. Y., a corporation of New York

Application May 7, 1942, Serial No. 442,072

2 Claims. (Cl. 113—120)

The invention relates to new and useful improvements in a method of flanging sheet metal can bodies, having a side seam with solder-bonded lap sections at the ends thereof.

One of the usual methods of flanging can bodies, consists in subjecting the formed can body to a flanging die which is shaped so as to expand and roll the edge portion of the can body outwardly into a flange which lies in a plane substantially at right angles to the longitudinal axis of the can body. This produces a curved section in the can body which joins the flange to the body portion of the can. The radius of this curvature is substantially uniform throughout the circumference of the can body except in the region of the side seam where the walls of the can body are lapped and solder-bonded together. During flanging these solder-bonded sections resist the flanging die so that the curvature is often on a greater radius, and this interferes with the forming of a tight seam all the way around the can body when an end is secured thereto. When the body is die-shaped from cylindrical form into a flanged end after solder-bonding, the solder is strained at the side seam due to the expansion of the metal to form the flange, and this straining of the solder-bond sometimes causes the solder-bond to snap and rupture.

An object of the present invention is to provide a method of flanging a can body, wherein the body wall which merges into the flange in the region of the lap sections is curved substantially on the same radius as the body wall in other regions.

A further object of the invention is to provide a method of flanging a can body, wherein the curvature of the body wall which merges into the flange in the region of the lap sections is pre-formed to a large extent before the solder-bonding takes place, so as to reduce the strain on the solder-bond during die shaping of the body wall in the final flanging operation.

A still further object of the invention is to provide a method of flanging can bodies wherein the body wall in the region adjacent the section from which the flange is to be formed and in the region of the lap sections is curved inwardly so as to reinforce and stiffen the portion of the can body through the side seam from one side of the can body to the other.

These and other objects will in part be obvious and will in part be hereinafter more fully disclosed.

In the drawing which shows a can body of the 55 curved rib 9 which is opposed to the recess 8.

lock and lap seam type flanged by my improved method,

Figure 1 is a view showing a portion of a can body having the hooks interlocked preparatory to bumping the side seam.

Fig. 2 is a view similar to Fig. 1 after the joined edges have been bumped preparatory to solder-bonding the same.

Fig. 3 is a sectional view on the line 3—3 of 10 Fig. 2 and showing in broken lines the formed flange.

Fig. 4 is a sectional view on an enlarged scale through the spline and the hammer showing the seam in its final bumped condition.

15 Fig. 5 is a view showing more or less diagrammatically a portion of the die for forming the flange partially entered into the can body preparatory to the flanging operation.

Fig. 6 is a view similar to Fig. 5 but showing 20 the flanging operation as completed.

Fig. 7 is a diagrammatic view showing the reinforcing rib extending across the body wall in the region of the side seam, the view being taken substantially on the line 7—7 of Fig. 2.

25 The method will be described as applied to the flange of a can body having a lock and lap side seam. This type of can body is well known and only brief reference is necessary to the features of construction.

30 The can body section 1 is joined to the can body section 2 by a side seam which includes hooks which are engaged with each other. These hooks terminate short of the ends of the can body so that there are lap sections only in the region 35 where the flange is to be formed. As viewed in Fig. 1, the can body is seen from the outside of the body and the outer lap is shown at 4 in full lines, while the inner lap is shown at 5 in broken lines.

40 The can body is formed in cylindrical shape about a horn and the hooks are interlocked after which they are bumped to bring them into very tight and intimate contact with each other. This is accomplished by a bumping iron or hammer 45 which is brought into contact with the outer face of the can body in the region of the interlocked hooks. The seam is bumped against the spline which is located in the horn. In Fig. 4 of the drawing a portion of the spline 6 and the bumping iron or hammer 7 are shown. In carrying out my improved method the spline is provided with a recess 8 which extends across the spline from one side thereof to the other. The bumping iron or hammer is provided with a

50 curved rib 9 which is opposed to the recess 8.

When the seam is bumped the body wall in the region of the hooks and the lapped sections adjacent the hooks will be curved inwardly, thus forming a rib on the inner wall of the can body which extends across the side seam and into the can body wall adjacent the side seam. This rib reinforces the body wall and greatly strengthens the same so as to prevent any hinge-like action on the seam formation which is likely to open the seam.

The spline 6 is also provided with a recess 10 which is curved on a radius conforming substantially with the curvature of the body wall merging into the flange after the flanging operation. This curving of the body wall is limited substantially to the region of the lap sections. The hammer 7 is provided with a rib 11 which is curved to conform to the curvature in the recess, and during the bumping operation the lap portions of the side seam are curved inwardly as indicated in Fig. 4 of the drawing.

The bridging member formed during the bumping operation through the cooperation of the rib 9 on the hammer and the groove 8 in the spline is indicated at 12 in the drawings. This rib is substantially straight and is in a sense a chord to the curvature of the cylindrical body. As shown in Figs. 2 and 7 the bridging rib extends through the side seam from one side of the can body to the other side. This rib is formed before the can body is solder-bonded. The solder-bonding of the seam is not shown in the drawing, as it is likely to confuse the same, but it is understood that when the side seam is solder-bonded, the solder will flow into the side seam throughout the limits thereof and join the contacting metal parts together.

During this bumping operation the rib 11 on the hammer cooperating with the recess 10 formed a curved portion 13 in the region of the lap sections, which curved portion is shaped so that it conforms substantially to the curved portion 14 which joins the finished flange 15 to the body wall. This curved portion 13 extends from a point 16 to a point 17. From the point 17 to the end of the can body the body wall is expanded into the flange. The flanging die used for forming the flange on the can body is indicated at 18. This flanging die has a portion 18a extending down into the can body below the rib 12 and is of such shape as not to deform this rib. It also has a portion 18b which is dimensioned so as to contact with the inner surface of the bead 13. The curvature of the bead 13 from the point 16 to the point 17 is closely approximated to the curvature of the flanging die from the point 18c to the point 18d, see Figs. 5 and 6. When the die therefore is forced down into the can body the upper end of the can body will be expanded and forced outwardly to form the flange. The beaded portion 13 will swing about the point 16 more or less as a hinge, for the reason that the curvature of the portion 13 approximates the curvature of the die which contacts therewith as the die moves on down for the flanging operation. In other words, this portion of the can body in the region of the lap sections has a preformed curve similar to the curve which joins the flange to the body wall, and it is moved outwardly during this flanging operation. As stated above, the flanging die when inserted into the can body expands the end of the can body into a flange and at the same time it positions the preformed curved portion in the lap section so that it merges

into the flange on substantially the same curvature as other portions of the body wall. This shaping of the body wall took place before the solder-bonding of the lap sections, and this pre-forming or curving of the body wall in the region of the solder-bonded lap sections greatly facilitates the expanding and shaping of the can body to form the flange without undue strain on the solder-bond.

10 It is well known that the grain of the metal forming the can body which is curved around a horn, extends in the general direction of the curvature of the body, and that it is parallel with the end edges of the can body. However, 15 when this section of the side seam is bumped so as to provide the curved portion 13 the grain in the curved portion will be changed so that it extends lengthwise of the seam and therefore the shifting of this curved portion 13 and whatever reshaping is necessary to provide the flange is aided by this change in the grain of the metal.

From the above it will be apparent that three things have been accomplished in my improved method of flanging, all of which cooperate to 25 the reducing of the strain in the solder-bond during flanging and the forming of a flange wherein the curved portion of the body wall merging into the flange is of a substantially uniform radius in the region of the side seam, as well as at other 30 points in the circumference of the can. One of the features is the pre-shaping of the metal in the lap sections prior to solder-bonding so as to facilitate the curving of the body wall in this region during flanging without undue straining 35 on the solder-bond. Another feature is the pre-curving of this section of the seam prior to solder-bonding so as to facilitate the forming of the flange so as to have a uniform curvature throughout to aid in the seaming of the end of the body in a very tight uniform seam. The 40 third feature is the forming of the reinforcing rib where the lap sections join the hook sections of the seam. This reinforcing rib extends across the seam transversely thereof and extends 45 into the body wall from one side of the can body to the other. This reinforcing rib stiffens the can body so as to prevent the seam from opening up by the hinging action of one of the hook 50 sections on the other and the rupturing of the solder-bond. This not only aids in the preventing of the rupturing of the solder-bond during packaging, but it also prevents rupturing of the solder-bond during storage of flanged can bodies 55 prior to the seaming of an end thereon. While a reinforcing rib is shown located at the junction of the hooks and the lap sections of the seam, it is understood that reinforcing ribs may be placed at other points along the side seam.

While the method has been described as applied to a can body of the type wherein the side seam has interlocked hooks and lap portions at the ends thereof, it is to be understood that my improved method of flanging may be equally applied to a side seam wherein the edge portions 65 are lapped throughout the entire length of the side seam.

I claim:

1. The method of flanging sheet metal can bodies having a side seam with solder-bonded lap sections at the ends thereof, consisting in bumping the lap sections of the side seam on a line parallel to the edge of the body and in the region where the lap sections are to be expanded and curved outwardly so as to merge into a flange, for curving said lap sections inwardly on a line of

curvature conforming substantially to the curvature of the body wall merging into the flange after flanging, solder-bonding the side seam, and subjecting said can body to a flanging die for expanding the end of the can body into a flange and positioning said preformed curved portion in the lap section so that it merges into the flange on substantially the same curvature as other portions of the body wall.

2. The method of flanging sheet metal can bodies having a side seam with solder-bonded interlocked hooks and lap sections at the ends thereof, consisting in bumping the lap sections of the side seam on a line parallel to the edge of the body and in the region where the lap sections are to be expanded and curved outwardly so as

5 to merge into a flange, for curving said lap sections inwardly on a line of curvature conforming substantially to the curvature of the body wall merging into the flange after flanging, also bumping the side seam in the regions where the ends of the hooks terminate for curving the same inwardly to form a reinforcing rib extending across the side seam from one side of the body to the other, solder-bonding the side seam and 10 subjecting the can body to a flanging die for expanding the end of the can body into a flange and positioning said preformed curved portion in the lap section so that it merges into the flange on substantially the same curvature as other portions of the body wall.

15 JOHN COYLE.
